[57] **CLAIM**

The ornamental design for a handled hair lift, as shown and described.

DESCRIPTION

FIG. 1 is a top perspective view of a handled hair lift showing my new design;

FIG. 2 is a front elevational view thereof, the rear side elevational view being a mirror image of the front view shown;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top perspective view of a second modified embodiment, the undisclosed sides being identical to the first disclosed embodiment except for the absence of oval convexities; and,

FIG. 8 is a front elevational view of a third modified embodiment, the rear view being a mirror image of the side shown. The undisclosed sides of FIG. 8 are identical to the first disclosed embodiment except for the appearance of the pattern on the comb teeth.
